UNITED STATES PATENT OFFICE

PETER J. MITCHELS, OF OAKLAND, CALIFORNIA

CONNECTION FOR DRAPERY RODS

Application filed May 16, 1928. Serial No. 278,282.

This invention relates to ornamental curtain and drapery rods.

In a certain type of interior decoration drapery rods are formed of twisted square wrought iron rods which have a very artistic appearance. These rods are fitted at their ends with ornamental devices and when used on bay windows the rods are formed in sections hinged together, so that they may lie parallel to the windows. The ornamental devices at the ends of the rod and the hinged connections are formed with square sockets to receive the ends of the rod. It is common practice to cut the rods to fit the windows when installing them and after the rods are cut the ornamental devices and the connections are fitted to the rods.

Hitherto, in order that the connections between the rods may lie in the proper plane and that the ornamental ends be properly disposed, it was necessary that the opposite ends of the rods be in absolute register. Due to the fact that the rods are cut to fit the windows during installation, the ends of the cut rods were in most instances out of register, necessitating that the rods be twisted to bring the ends in register. This latter operation is a difficult one requiring equipment and adds to the cost of installation.

It is the principal object of the present invention to overcome the disadvantages of this prior method by providing means enabling the connecting and ornamental devices to be expeditiously and properly arranged on the rods regardless of the disposition of the ends thereof.

In carrying this object into practice, the hinged connections for connecting the rods together and the ornamental devices fitted to the ends of the rod are formed with sockets which may be turned to register with the rods so that the hinged connections and ornamental devices may be properly disposed regardless of the position of the ends of the rod.

One form which the invention may assume is exemplified in the following description and illustrated by way of example in the accompanying drawings, in which:

Fig. 1 is a view in perspective of a curtain

rod showing ornamental devices fitted to the ends thereof.

Fig. 2 is a side elevation of one of the ornamental ends partially in section to disclose the construction thereof.

Fig. 3 is an end view of the ornamental ends shown in Fig. 2.

Fig. 4 is a perspective view showing one form of connecting device for connecting two rods together.

Referring more particularly to the accompanying drawings, 10 indicates a drapery rod having ornamental devices 11 fixed at its ends. The inner end of each ornamental device is fitted with a socket 12 having a square recess 14 formed within the inner end thereof. The other end of the socket 12 abuts against the ornamental device 11. A screw 15 projects axially through the outer end of the socket 12 and is threaded into the adjacent end of the ornamental device 11. By loosening this screw the socket 12 may be turned so that the squared recess 14 may accommodate the end of the drapery rod 10. This rod as shown in the drawings is formed of a square wrought iron bar which is twisted to give it an artistic appearance.

Hitherto, the sockets 12 were formed integral with the ornamental ends so that it was necessary to twist the rods so that their opposite ends registered in order that the ornamental devices 11 would be properly positioned.

In the present instance it is only necessary to cut the rod to the proper length, adjust the sockets 12 with relation to the ornamental ends 11 and then tighten the screws 15. To secure the sockets on the rod they are provided with set screws 16 which project into the recesses 14 so that the sockets may be clamped to the ends of the rod.

When a drapery rod of this character is fitted to bay windows, the rod sections for the windows are connected at the corners by hinged devices such as shown in Fig. 4. These hinged devices are fitted with sockets 12 of the same construction as shown in Fig. 2. These sockets 12 are secured to the hinge in the same manner as the socket 12 is secured to the ornamental ends 11. By this construction the rods may be properly con-

nected and fitted with ornamental ends in an expeditious manner regardless of whether or not the ends of the rod are in register.

In use, the rod is cut to fit the window and the screws 15 are loosened so that the sockets 5 may be adjusted to accommodate the disposition of the ends of the rod. When properly adjusted, the screws 15 are tightened and the devices are fitted to the ends of the rod. The set screws 16 are then taken up to clamp the 10 sockets to the rod. By having the sockets rotatable or turnable with respect to the devices 11 and the hinge connection between the rods, the rods may be more expeditiously assembled on windows than hitherto.

15 While I have shown the preferred form of my invention, it is to be understood that various changes may be made in its construction by those skilled in the art without departing from the spirit of the invention as defined in 20 the appended claims.

Having thus described my invention, what I claim and desire to secure by Letters Patent is:

- 25 1. In combination with a twisted square drapery rod, an ornamental device adapted to be fitted to the end thereof, said device including a socket adapted to receive the end of the rod, means connecting said socket to said device permitting the socket to be turned relative to the device or relatively fixed thereto.
- 30 2. In combination with a twisted square drapery rod, a socket member having a square recess to receive the end of the rod, an ornamental device at the outer end of the socket, a screw projecting axially through the socket member and threaded into the device whereby the socket member may be turned on its axis relative to the device or relatively fixed to the device.
- 35 40 3. A device of the character described comprising a drapery rod formed of a twisted bar square in cross section, a socket member having a square recess to receive the end of the rod, an ornamental device adapted to be fitted to the outer end of said socket member to form a finished end for the rod, a screw connection between the socket member and said ornamental device, said connection being at the longitudinal axis of the socket and said ornamental device and permitting said ornamental device to be adjusted about the axis of the rod.

PETER J. MITCHELS.
